UNITED STATES PATENT OFFICE.

PAUL SCHMIDT, OF VIENNA, AUSTRIA-HUNGARY.

TOOL-GRINDER.

1,130,112.

Specification of Letters Patent. Patented Mar. 2, 1915.

Application filed October 22, 1913. Serial No. 796,656.

To all whom it may concern:

Be it known that I, PAUL SCHMIDT, managing director, a subject of the King of Prussia, and a resident of 30 Ybbsstrasse, Vienna, II, in the Empire of Austria-Hungary, have invented a Tool-Grinder; and I do hereby declare the following to be a full, clear, and exact description of the invention, such as will enable others skilled in the art 10 to which it appertains to make and use the same.

My invention relates to tool grinding machines and, particularly, to grinders for grinding toothed cutting tools, and a primary object is to provide a grinder in which the movement of the rotating grinding wheel relatively to the work piece is caused by the axle which carries the grinding wheel being mounted eccentrically or slantwise in 15 a shaft so that when the latter rotates the grinding wheel is moved bodily relatively to the workpiece and is moved toward and away from the same.

To this end, my invention consists in the 25 construction, arrangement and combination of parts described hereinafter and pointed out in the claims.

One embodiment of my invention is represented by way of example in the accompanying drawing, wherein:—

Figure 1 is an elevation of a grinder for grinding saw-blades, Fig. 2 is a horizontal section thereof, and Fig. 3 is a diagram showing the eccentrically mounted grinding-wheel axle and the reciprocatory motion of the grinding wheel produced thereby.

Referring to the drawing, the grinding wheel *a* is fast on the axle *b* which, in the illustrative embodiment, is eccentrically 40 journaled in the shaft *c*. The axle *b* is driven by the belt-pulley *d* and the shaft *c* by the belt-pulley *e*. In consequence of the grinding wheel *a* being mounted eccentrically, during each revolution of the shaft *c* 45 the grinding wheel must move once to and fro, and this movement suffices to cause the same to enter into the gaps between the teeth of the saw-blade *f* and to grind the teeth. I provide that the shaft *c* also causes

the saw-blade *f* to be rotated. To this end, 50 the one end of this shaft is formed as a cam *g*. This cam occupies such a position relatively to the eccentric bore in the shaft that the saw-blade is fed forward while the grinding wheel is farthest therefrom. The 55 motion of the cam *g* is transmitted by the anti-friction roller *h* to the lever *i* which is fulcrumed at one end on the pivot *k* and carries at its other end a braking spring *l* which drives the saw-blade in the direction 60 indicated by the arrow. When the lever rocks back the saw-blade is held by the locking spring *m* while the breaking spring *l* slides over the saw-blade. The spring *o* holds the roller *h* of the lever *i* constantly in 65 contact with the cam *g* of the controlling shaft *c*. The saw-blade rotates freely on the pin *p* of the carrier *r* which can be shifted on the rod *s*.

What I claim as my invention and desire 70 to secure by Letters Patent is:

1. A tool grinder comprising a shaft, an axle journaled eccentrically in said shaft, a grinding wheel carried by said axle, means for driving said shaft, and means for independently driving the axle of the grinding 75 wheel.

2. In a tool grinder, the combination of a shaft having an eccentric bore longitudinally through the same, an axle in said bore, 80 a grinding wheel on the axle, and workpiece feed-mechanism actuated by said shaft, substantially as described.

3. In a tool grinder, the combination of a shaft having an eccentric bore longitudinally through the same, an axle in said bore, a grinding wheel on the axle, one end of the shaft constituting a cam, and workpiece feed-mechanism actuated by said cam, substantially as described. 85

In testimony whereof I have signed my name to this specification in the presence of two subscribing witnesses:

PAUL SCHMIDT.

Witnesses:
